Specification for Design.

Patented Jan. 4, 1916.

Application filed September 3, 1915. Serial No. 48,894. Term of patent 7 years.

To all whom it may concern:

Be it known that I, ROBERT R. KINTZ, a citizen of the United States, residing at Meriden, county of New Haven, State of Connecticut, have invented a certain new, original, and ornamental Design for Handles for Spoons, Forks, or Similar Articles, of which the following is a full, clear, and exact description, reference being had to the accompanying drawings, forming part hereof.

In the drawings, Figure 1 is a plan view showing the handle attached to a spoon in full lines and a fork in dotted lines. Fig. 2 is a cross section of the handle at its largest part. Fig. 3 shows a side view of the handle.

I claim:

The ornamental design for a handle for spoons, forks and similar articles, as shown.

ROBERT R. KINTZ.
